(57) **CLAIM**

The ornamental design for a dust ruffle with storage pockets, as shown and described.

DESCRIPTION

FIG. 1 is a front elevation view showing three pockets with each pocket including a cover flap.

FIG. 2 is a rear elevation view.

FIG. 3 is a right side elevation view showing four pockets which include hook and loop closures at their tops and one pocket which also includes an outside slash pocket.

FIG. 4 is a left side elevation view showing four pockets which include hook and loop closure at their tops.

FIG. 5 is a top view; and,

FIG. 6 is a bottom view.

The broken lines on the pockets of the dust ruffle with storage pockets represent stitching.
